G. Kennedy,
Attorney.

UNITED STATES PATENT OFFICE.

FRANK A. ROOSA, OF ORANGE TOWNSHIP, BLACKHAWK COUNTY, IOWA, ASSIGNOR
TO PIONEER MANUFACTURING COMPANY, OF WATERLOO, IOWA, A CORPORATION
OF IOWA.

FILLER-BODY FOR PACKER-HEADS OF TILE-MACHINES.

1,355,913.

Specification of Letters Patent. Patented Oct. 19, 1920.

Application filed December 9, 1919. Serial No. 343,539.

To all whom it may concern:

Be it known that I, FRANK A. ROOSA, a citizen of the United States of America, and resident of Orange township, Blackhawk county, Iowa, have invented certain new and useful Improvements in Filler-Bodies for Packer-Heads of Tile-Machines, of which the following is a specification.

My invention relates to improvements in 10 filler-bodies for former-heads of tile machines, and the object of my improvement is to perfect the operation of machines for forming hollow tile from concrete, while, at the same time, effecting a great reduction in 15 the amount of power required for performing the operation.

This object I have accomplished by the means which are hereinafter described and claimed, and which are illustrated in the accompanying drawings, in which Figure 1 is a vertical central section of a hollow mold and pallet, showing a rotatable former-head within the mold, parts of said head being shown in vertical central section. Fig. 2 is a horizontal section of said mold and former head, taken on the broken line 2-2 of Fig. 1. Fig. 3 is a top plan view of said mold and former head, the shaft of the latter being in cross section. Fig. 4 is an enlarged 25 perspective view of the covering plate and of filler-bodies adjustably mounted thereon. Fig. 5 is a perspective view of a former-head having a larger number of troweling-projections, and equipped with my improved 30 filler-bodies. Fig. 6 is a plan view of the covering plate used with the former-head shown in said Fig. 5, and Fig. 7 is a perspective view of a filler-body of the type used in connection with the covering-plate 35 shown in said Fig. 6.

Similar numerals of reference denote corresponding parts throughout the several views.

Referring to Fig. 1, the numeral 7 denotes 45 a simple form of mold, of hollow cylindrical form, supported upon an annular pallet 8 and concentric therewith. The numeral 6 denotes an operating shaft which may be rotated and also simultaneously reciprocated 50 centrally within and through the mold 7 by mechanism of any desired type.

Upon the lower end of said shaft is coaxially secured a former-head which is rotatable therewith, and whose outer circumfer-

ence is spaced from the inside wall of the 55 mold 7 a distance equal to the thickness of a hollow tile to be formed between them from concrete deposited within the open upper end of said mold. The former-head comprises a depending hollow cylindrical 60 smoothing body 1, having a central threaded orifice to receive the exteriorly threaded lower end of said shaft at 5. Curved projections or abutments 3 extend oppositely and laterally also vertically, from the shaft 65 6 immediately above the body 1. The numeral 2 denotes troweling-bodies, crescental in cross-section, which are secured upon the convex faces of the abutments 3 by means of bolts 4, in order to be replaceable by others 70 of different dimensions, or when worn out. In Figs. 1 to 4, inclusive, where there are but two troweling bodies 2, the covering-plate 13 and pair of filler-bodies 9 are appropriately formed for adjustable connection to 75 each other and to properly inclose the inner parts of the interspaces of the troweling-bodies.

In Figs. 5 to 7, inclusive, said parts 13 and 9 are slightly modified in form to serve the 80 above purpose for use with a former-head having a larger number of troweling-bodies, in this case, four.

The covering plate 13 is flat, and provided with a central opening 14 to seat it 85 about the shaft 6 so that it may be supported upon the tops of the troweling bodies 2. Said plate is provided with a plurality of curved slots 11 equidistant and near its edge for a purpose to be described. The numeral 90 9 denotes a filler-body having a segmental curved vertical wall and an inwardly extended horizontal ledge 10 which in whole or in part, according to adjustment, underlies parts of the lower surface of the plate 95 13, and is removably adjustably secured thereto by bolts 12 traversing bolt-holes 15 in the ledge 10 and a curved slot 11 in the plate 13. It will be seen that when these connected elements are assembled with the 100 troweling-bodies 2, they are mounted between said bodies completely inclosing the inner parts of the interspaces of said bodies, but leaving exposed sufficient of the troweling surface of said bodies and receiving 105 space adjacent thereto as may be necessary for the successful functioning of the former-head. As shown in said Fig. 2, the

- filler-body walls are curved in such a manner that when mounted on the former-head, the concrete receiving space above the basal part 1 is widest adjacent the convex troweling surface of each troweling-body. This affords sufficient room for the reception of the descending concrete, the other end of the space being made narrow because not needed.
- 10 In the former practice, where former-bodies of the type shown have been used, but without the use of my said filler body, large interspaces are left between the troweling-bodies which receive and become filled up with masses of concrete materials. In the operation of the device, these masses engorge the former-head causing much friction and loss of power. Also, detached masses are at times projected outwardly and being often of different consistency than the average mixture supplied, produce bodies of different degrees of density in the tile, changing its homogeneity, which irregularity may lead to failure of the tile. When 25 my said filler-bodies are used, as shown, said interspaces of the troweling-bodies are so narrowed that only sufficient clearance is left adjacent the troweling bodies for their efficient functioning as the mixture is supplied. Much friction is thereby obviated, in fact, the power necessary amounts to but a small fraction of that employed when the filler bodies are not used. The filler bodies may be varied in shape as desired.
- 30 35 Having described my invention, what I claim as new, and desire to secure by Letters Patent, is:

1. A former-head for a tile machine, having spaced troweling projections, and filler-

bodies within the inner parts of the inter-spaces of said projections. 40

2. A former-head for a tile machine, having spaced troweling projections, and filler-bodies removably mounted within the inter-spaces of said projections. 45

3. A former-head for a tile machine, having spaced troweling projections, and filler-bodies adjustably mounted within the inter-spaces of said projections.

4. A former-head for a tile machine, having spaced troweling projections, a cap-body mounted over said projections, and filler-bodies on said cap-body extending between said projections. 50

5. A former-head for a tile machine, having spaced troweling projections, a cap-body mounted removably over said projections, and filler-bodies removably mounted on said cap-body and depending to inclose the inner parts of the interspaces of said 60 projections.

6. A former-head for a tile-machine, having a basal smoothing cylinder and spaced troweling projections above said cylinder, and filler-bodies mounted upon said cylinder 65 between said projections.

7. A former-head for a tile machine, having a basal smoothing cylinder and spaced troweling projections thereabove, a plate positioned removably upon said projections, 70 and filler-bodies adjustably mounted upon said plate and depending into the inter-spaces of said projections toward said cylinder.

Signed at Waterloo, Iowa, this 1st day of 75 Dec., 1919.

FRANK A. ROOSA.
